UNITED STATES PATENT OFFICE.

CHARLES F. HUMPHREYS, OF LANCASTER, PENNSYLVANIA, ASSIGNOR TO ARMSTRONG CORK COMPANY, OF PITTSBURGH, PENNSYLVANIA, A CORPORATION OF PENNSYLVANIA.

LINOLEUM FLOOR-COVERING.

1,129,571.

Specification of Letters Patent.

Patented Feb. 23, 1915.

Application filed April 11, 1913. Serial No. 760,476.

To all whom it may concern:

Be it known that I, CHARLES F. HUMPHREYS, a subject of the King of Great Britain, and a resident of Lancaster, in the county of Lancaster and State of Pennsylvania, have invented a new and useful Improvement in Linoleum Floor-Covering, of which the following is a full, clear, and exact description, reference being had to the accompanying drawings, forming part of this specification, in which—

Figure 1 is a plan view showing a portion of my improved linoleum of the inlay type. Fig. 2 is a longitudinal section of the same. Fig. 3 is a view similar to Fig. 1, showing the plain or printed type, and Fig. 4 is a longitudinal section of Fig. 3.

My invention relates to the class of linoleum floor coverings in which a linoleum mixture is applied upon and secured to a backing or foundation material. This linoleum mixture may be of the usual type, containing either pulverized cork or wood-flour in combination with a drying oil, such as linseed oil; pigments, gum or rosin also being used in the mixture, if desired. These mixtures oxidize on exposure to the air.

Heretofore both in the case of plain or printed and inlay linoleum, the backing or foundation has been made of a textile fabric, such as burlap or other fabric made from jute or other woven textile material. This woven textile material is of relatively high cost and increases the cost of the finished linoleum.

I have discovered that by using the water-proof paper as the backing or foundation material, instead of burlap or a woven textile material, I can greatly decrease the cost of linoleum and also reduce the tendency to buckling or waving of the product while giving a satisfactory strong material.

In carrying out my invention for plain or printed linoleum, I preferably take a heavy impregnated water-proof paper in rolls and pass it through the linoleum machine, thereby hot rolling upon this paper

a linoleum mixture such as this above described. This linoleum mixture firmly adheres to the paper which gives a satisfactory, cheap backing or foundation therefor. In carrying out this process with the paper backing or foundation, I preferably do away with the tension which has heretofore been put on the burlap or textile material to keep the same from buckling in the rolls. This tension which is given the burlap material now used, tends to cause buckling or waving of the linoleum and I avoid this tendency by hot rolling the linoleum material on the paper backing or foundation on the paper. In the case of the inlaid linoleum, I follow the usual process of rolling or pressing the inlay blocks or granulated composition on the paper backing or foundation, using any well known type of inlay machine for this purpose.

In the drawings, referring to Figs. 1 and 2, 2 represents the paper backing or foundation, and 3 the inlaid linoleum. In Figs. 3 and 4, 4 represents the paper backing or foundation, and 5 the sheet linoleum applied thereto, which may be either plain or printed.

I am aware that floor coverings have been formed, the body of which consists of paper provided with a decorated or printed surface, the pattern being printed in oil or other colors; but to my knowledge a paper backing or foundation has never been used for linoleum floor covering.

The advantages of my invention result from cheapening the cost of material, as well as from doing away with the liability to buckling, and providing a cheap, strong, efficient floor covering. The paper which I use, preferably has a rough surface to more thoroughly unite with the linoleum layer and this paper may be of any type, made from any kind of matted fibers, as distinguished from a woven fabric.

Many variations may be made in the paper backing or foundation employed, as

well as in the details of the linoleum composition, so long as this composition is of the true linoleum type.

I claim:

- 5 1. A linoleum floor covering, composed of a water-proof paper backing or foundation provided with a wearing surface of linoleum mixture, substantially as described.
2. A linoleum floor covering composed of
- 10 a paper backing or foundation having a

linoleum layer thereon, the linoleum layer being at least as thick as the paper, substantially as described.

In testimony whereof, I have hereunto set my hand.

CHARLES F. HUMPHREYS.
